cialties, Inc., Chicago, Ill., a corporation of Illi-
nois

Application June 9, 1948, Serial No. 31,984

14 Claims. (Cl. 29—33)

1

Our invention relates to a feed for power presses and more particularly to an assembly in combination with a power press for carrying the feed rolls up and down with the stock when drawing or forming operations are such that it is necessary to raise the stock to clear the die cavities before it is possible to feed the stock to the next operation.

Many objects are formed on power presses by means of progressive dies requiring successive steps in which a plurality of stations are provided in a die or dies such that the stock is moved from station to station in successive steps.

At each station, one operation is performed so that at the final station the complete object, having the desired form and shape, is finally achieved. In operations of this character, the dies are frequently provided with re-entrant portions and it becomes a difficult matter to feed the stock from station to station. In operations requiring the raising and lowering of the stock, die designers make dies for separate operations, each to be conducted in a different press. Stock is fed by hand and transferred from press to press, either on conveyors or by hand, and fed to succeeding presses by hand. Our invention permits such operations to be performed on progressive dies, using oiled stock, thus saving machinery, conveyor equipment, man power and space.

One object of our invention is to provide a power press in which progressive dies formed with re-entrant portions may be fed with stock automatically by a double roll feed.

Another object of our invention is to provide an improved power press having a roll feed in which the feed rolls are carried up and down in a predetermined phased relation when drawing or forming operations are such that it is necessary to raise the stock to clear the die cavities before it is possible to feed the stock to the next operation.

Another object of our invention is to provide an improved power press assembly having a roll feed in which the feed rolls are reciprocated in a predetermined timed relation to the operation of a press ram and with the working of the die and the lift-out mechanism.

Another object of our invention is to provide a power press having feed rolls moving up and down in a predetermined timed relation and provided with a scrap cutter whose operation is timed with the press ram and the feed roll and lift-out movement in such manner as to provide a continuous feeding of the stock.

Other and further objects of our invention will appear from the following description.

2

In general our invention contemplates the provision of a framework adapted to reciprocate on the press frame independently of the press ram. The framework carries a pair of feed rolls. Driving means are provided for reciprocating the framework in timed relation to the movement of the press ram such that the stock will occupy one level clear of the die cavities during feeding and will be in position for the forming or a drawing operation during the working stroke of the ram. The framework carrying the feed rolls is adapted to operate the lift-out pins in the dies.

In combination with the above, we may provide if desired a scrap cutter which moves up and down agreeable to the movement of the stock which may be operated by an eccentric in predetermined timed relation or which may be operated by the motion of the reciprocating lift-out framework.

20 In the accompanying drawings which form part of the instant specification and which are to be read in conjunction therewith and in which like reference numerals are used to indicate like parts in the various views:

25 Figure 1 is an elevation of the press with a typical die in section showing one embodiment of our invention;

Figure 2 is a side elevation taken along the line 2—2 of Figure 1 showing a scrap cutter having a full width blade;

30 Figure 3 is a fragmentary elevation taken along the line 3—3 of Figure 2, with parts in section, showing the scrap cutter drive;

Figure 4 is a side elevation similar to Figure 32 showing a scrap cutter of a different type operated by the motion of the lower lift-out relative to the press frame;

Figure 5 is a fragmentary view taken along the line 5—5 of Figure 4 showing details of the scrap 38 cutter drive shown in Figure 4;

Figure 6 is a timing diagram showing the cycle of operations of the press ram, the scrap cutter of the form shown in Figure 2 and the lower lift-out beam; that is the framework carrying the 45 feed rolls.

More particularly, referring now to the drawings, a press frame indicated generally by the reference numeral 10 supports a crown 12 on which is supported a prime mover such as an 50 electric motor 14. The motor 14 drives a flywheel 16 through a plurality of V-belts 18 or in any other appropriate manner. The flywheel is adapted to be clutched to and unclutched from a main driving pinion 20 as is well known in the art. The pinion 20 drives a gear wheel 22 which

meshes with a gear wheel 24. The gear wheel 22 drives a pinion 26 while the gear wheel 24 drives the pinion 28. The pinion 26 drivingly meshes an eccentric gear 30 while the pinion 28 drives an eccentric gear 32. The eccentrics are connected to a slide 34 through pitmans (not shown) as is well known in the power press art so that the slide is adapted to reciprocate in predetermined timed relation, usually with simple harmonic motion.

The slide 34 carries a slide bolster 36. The bed of the press 38 is provided with a bed bolster 40.

In Figure 1, a six-station die is shown in which there are provided a plurality of die cushions in the slide. In the drawing, an upper lancing die 42 is positioned between the first station which is idle and the second station which is idle and is provided with a die cushion 44 for stripping of stock. At the third station, the upper drawing die 46 is provided with a die cushion 48 to act as a blank holder. At the fourth station, an upper piercing die 50 is provided with a die cushion 52 for stripping of stock. At the fifth station, an upper redrawing die 54 is provided with a die cushion 56. At the sixth station, an upper trimming die 58 is provided with a die cushion 60. On the bed bolster 40, a lower die, or dies, is positioned upon the bed bolster 40 for cooperation with the corresponding and co-acting upper dies.

A pair of gear boxes 62 and 64 are carried by the crown of the press. A gear 66 meshes with eccentric gear 30 for rotation thereby and a gear 68 is rotated from eccentric gear 32. A gear 70 is housed within the gear box 62 and meshes with a pinion 72 driven by gear 66. A pinion 74 is adapted to rotate with gear 68 and meshes with gear 76 housed within gear box 64. The power ranges are such that the shaft 77, carrying the cam 78, will rotate at the same speed as the gear 30 and the cam 80 will rotate at the same speed as the gear 32. A pair of cams 78 are adapted to be driven by the rotation of gear 70. A pair of cams 80 are adapted to be driven through gear 76. A pair of levers 82 are pivotally secured to a pair of lugs 84 carried by the press crown. A pair of lever 86 are pivotally secured to lug 88 secured to the crown of the press 12. The ends of levers 82 are bifurcated and pivotally connected to a pair of supporting rods 90, the lower ends of which are pivotally secured to lugs 92 carried by a feed roll-supporting framework 94. The lever 82 are provided with a pair of cam followers 96 engaging respective cams 78. The arrangement is such that the rotation of cams 78 will move the roll-supporting framework 94 up and down with a motion depending upon the shape of the cam. The cams 78 are secured to a shaft 77 for rotation therewith. The shaft 77 operates a shaper motion lodged within housing 98 adapted to reciprocate member 99 to which a rack 100 is connected, rotating a drive pinion secured to a shaft 102 adapted through intermeshing bevel gears to rotate the drive shaft 104 through an overrunning clutch as is well known to the art. The rotation of the drive pinion through the rack 100 also rotates connecting shaft 106, rotating roll feed drive shaft 108 through a pair of bevel gears 110. The drive shaft 104 is splined to sleeve 112 such that the sleeve may reciprocate relative to the drive shaft 104. Rotation of the sleeve 112 will operate the feed rolls 114 and 115 through gears in gear box 113. The upper position of the feed rolls is shown by ref-

erence numerals 114 and 115. The lower position of the feed rolls is shown by the reference numerals 114a and 115a.

Similarly the lower end of roll feed drive shaft 108 is housed in a splined sleeve 116 such that the sleeve 116 may reciprocate relative to the drive shaft 108 and drive the feed rolls 118 and 119 through appropriate gearing. The upper position of the feed rolls driven by the shaft 108 is shown by the reference numerals 118 and 119. The lower position of the feed rolls is shown by the reference numerals 118a and 119a.

The levers 86 carry cam followers 120 similar to cam followers 96. The ends of levers 86 support a pair of tension rods 122 similar to tension rods 90. The lower ends of rods 122 are pivotally secured to a pair of lugs 124 carried by the roll feed-supporting framework 94. A lift-out bar 126 is likewise carried by the framework and adapted to reciprocate with it.

The bed bolster carries a die 41 intermediate the idle first station and the idle second station adapted to cooperate with the upper lancing die 42. The bed bolster 40 carries a die 45 adapted to cooperate with the upper drawing die 46 at the third station. The lower die is provided with a stripper pad 128. Stripper pins 130, adapted to be actuated by the lower lift-out bar 126, contact the lower surface of the stripper pad 128. A lower piercing die 49 cooperates at the fourth station with the upper piercing die 50 and is provided with a stripper pad 132, the lower surface of which contacts stripper pins 134, adapted to be actuated by the lower lift-out bar 126. At the fifth station, we provide a lower redrawing die 53 adapted to cooperate with the upper redrawing die 54. The lower redrawing die 53 is provided with a stripper pad 136, the lower surface of which is in contact with stripper pins 138, adapted to be actuated by the lower lift-out bar 126. At the sixth station, we provide a trimming die 57 adapted to co-act with the upper trimming die 58, the finished piece adapted to drop as shown by the dotted-line position and the arrow. It is to be understood of course that any desired die arrangement may be used, the particular die arrangement shown being for purposes of illustration only and not by way of limitation.

In Figure 1, the stock enters the initial feeding rolls 118 and 119 and is fed to the left by the conjoint action of rolls 118 and 119 and rolls 114 and 115 which are moved in timed relation by a common drive while the rolls are in the upper position shown by the line indicated by the reference numeral 140. The stock in the process of being formed is in the position indicated by the reference numeral 142 during the working part of the cycle. The stock material, after the shapes being pressed in the press have been trimmed from the sheet, moves to the left and comes into contact with a scrap cutter.

In the form of the scrap cutter shown in Figures 2 and 3, an eccentric 144 is secured to shaft 77 which is rotated by the gear 70 meshing with pinion 72. Rotation of the eccentric reciprocates a pitman 146 secured thereto in predetermined timed relation. The lower end of pitman 146 is secured to a connecting member 148 carried in a housing 150. The member 148 is provided with a screw 152, the position of which is adjusted by nut 154, the periphery of which is provided with a worm gear cooperating with a worm 156. The worm 156 is rotated by hand wheel 158 and is adapted to adjust a blade holder 160 to which the upper cutting blade 162 is secured. The blade

holder 160 is adapted to reciprocate in a pair of guides 164. The lower blade 166 is carried by the frame 93 which is fastened to the bed of the press. The operation of the scrap cutter is timed so that the scrap is cut after the feeding motion has taken place and the feed is in the lowermost position.

In the form of the invention shown in Figures 4 and 5 where the scrap comprises strips at each edge of the stock, the scrap cutter need not extend the full width as shown in Figures 2 and 3. In such a case, the scrap cutter may be operated by the motion of the roll-carrying framework.

Referring now to Figure 4, the scrap cutter comprises a pair of lower blades 170 which are fixed to the reciprocating roll-carrying framework 94. The press frame 10 carries a pair of lugs 172, each having an adjustable screw 174. The upper blades of the scrap cutters 176 are pivoted. As the lifting rods 90 and 122 move the framework carrying the rolls 114 and 115 upwardly, rollers 178 carried by extensions of the upper blades 176 engage the screws 174 so as to pivot the upper blades 176 to open position, thus insuring that the cutters are in open position during the roll-feeding movement. While in this position, the roll-feeding drive mechanism operating through drive shaft 104 and splined sleeve 112 and associated gearing rotate the feeding rolls 114 and 115 to move the stock being fed through a predetermined distance. A lower pair of lugs 180 carried by the press frame carry adjustable screws 182. As the roll-carrying framework moves downwardly, the screws 182 will engage rollers 178 to pivot the upper blades 176 to closed position, thus effecting the cutting of the scrap. This type of scrap cutter is adapted only for operations using one width of stock. If different widths of stock are to be used, a scrap cutter running the entire width of the rolls is preferred.

In operation, the stock 142 is threaded to the second station and the press set into operation. The cams 78 and 80 will move about 140° from the position shown in Figure 1, permitting the stock to lie over the lower die. The press completes its cycle and the lancing die 42 will lance the end of the stock at a point between the first and second stations which are idle. As the cycle continues, the cams 78 and 80 will return to the position shown in Figure 1 and pull rods 90 and 122 will lift the framework upwardly to move the stock and the feeding rolls to the level shown by construction line 140 in Figure 1. While the stock is in this position, the roll-feeding mechanism will be actuated to rotate the rolls just sufficiently to move the end of the stock one station. The end of the stock is now in the third station and the dies 46 and 45 will cooperate to perform the first draw. As the cams again lift the roll-carrying framework and the lower lift-out bar 126 upwardly, the stripper pins 130 will move the blank holding pad 128 upwardly to move the stock again to the position level of the construction line 140 so that the cupped portions are clear of the re-entrant portions of the die. In this position, the feeding rolls are again operated by the roll feeding mechanism to roll the stock through one station, bringing a fresh portion of the stock to the third station and moving the stock which formerly occupied the third station to the fourth station. The cycle of the press then continues to lower the stock to the die surface by the operation of cams 78 and 80. The press drive train operates the press slide and the upper bolster seats the upper dies into their co-acting

lower dies. At the third station, the first draw is again performed on a fresh section of the stock while at the fourth station die 50 cooperates with die 49 to pierce the stock which has been subjected to the first draw. As the two pairs of cams 78 and 80 move the draw bars 90 and 122 upwardly, the roll-carrying framework moves upwardly, together with the lower lift-out bar 126. The stripper pins 130 move the pad 128 of the die 45 upwardly and the stripper pins 134 move the stripper pad 132 upwardly so that the cups at the third and fourth stations are moved out of the lower dies to the level indicated by the construction line 140 along with the feeding rolls. While the feed roll-carrying framework and the lower lift-out bar are dwelling in the upper position, the roll-feeding mechanism is again operated to move the stock to the left, as viewed in Figure 1, through one station. Fresh stock is now brought to the first draw, the portion of the stock subjected to the first draw is brought to the fourth station for action by the piercing dies and the stock which has been subjected to the first draw at the first station and pierced at the fourth station is now in position at the fifth station. The continuation of the cycle drops the feed roll-carrying framework and the lift-out bar, permitting the stock to move to the position shown in full lines in Figure 1. At the fifth station, the stock is subjected to a redrawing operation by the co-action of dies 53 and 54, dies 50 and 49 cooperating to pierce, and dies 45 and 46 cooperating to perform the first draw. When the feed roll-carrying framework is again moved upwardly, not only do the stripper pins 130 and 134 operate but the stripper pins 138 co-act with the stripper pad 136 to lift the stock subjected to the redrawing operation at the fifth station so that all of the stock and the feed rolls is lifted clear of the lower dies. While the stock dwells in this position, the feed rolls again operate to move the stock to the left through another station. This brings the stock occupying the position at the third station to the fourth station, that occupying the fourth station to the fifth station and that occupying the fifth station to the sixth station. The cycle is again performed by the press and the stock at the sixth station is trimmed by the co-acting trimming dies 57 and 58 so that the formed part drops as shown by the arrow. Another cycle brings the end of the stock to the feed rolls 114 and 115 which are operated by a drive mechanism in common with the drive mechanism for feed rolls 118 and 119. The stock will then move step-by-stepwise with operations between movements to the left. Just after the stock has been advanced while in the upper period of dwell of the roll-carrying framework, the eccentric which drives the scrap cutter moves the pitman 146 and the upper blade 162 downwardly to cut the end of the used stock into a strip of scrap.

The scrap cutter has a long stroke so that the blade 162 is above the stock while the stock is being fed and moving down. At about 140° of the eccentric gear motion, the downward motion stops. The scrap cutter blade continues downwardly and cuts off the scrap.

The timing of the motions of the slide, the scrap cutter and the lower lift-out in a typical case is shown in Figure 6.

In the form of the invention shown in Figure 5, the upper adjusting screws 174 insure that the blades are open during the period in which the roll feed operates to feed the stock through the

predetermined distance. As the draw rods permit the roll-carrying framework to move downwardly the lower adjusting screws 182 operate the upper scrap cutting blades 176 to cut the scrap.

It will be seen that we have accomplished the objects of our invention. We have provided a power press in which progressive dies formed with re-entrant portions may be fed with stock material automatically by a double roll feed in which the feed rolls are carried up and down in a predetermined timed relation. The stock is thus carried clear of the die cavities during the period in which the stock is fed for the next operation. The roll-carrying framework is reciprocated in phased relation with the press slide and with the operation of the die lift-out mechanism. We have provided a power press having a roll feed moved to a position clear of the die cavities during the feeding of the stock in combination with the scrap cutter whose operation is timed with the press ram feeding rolls and lift-out movement in such manner as to provide a continuous feeding of the stock with the cutting of the ends of the used stock into scrap.

It will be understood that certain features and subcombinations are of utility and may be employed without reference to other features and subcombinations. This is contemplated by and is within the scope of our claims. It is further obvious that various changes may be made in details within the scope of our claims without departing from the spirit of our invention. It is therefore to be understood that our invention is not to be limited to the specific details shown and described.

Having thus described our invention what we claim is:

1. In a power press, a slide, a bed bolster, driving means for reciprocating said slide, means adapted to support a die on the bed bolster, means adapted to support a co-acting die for cooperation with the die carried by the bed bolster, a movable frame, stock-feeding rolls carried by said frame, means drivingly connecting said frame to said slide-driving means for reciprocating said frame vertically in predetermined timed relation with said slide, and means driven from said slide-driving means for operating said feeding rolls in predetermined phased relation with the movement of said feed roll-carrying frame.

2. In a power press, a slide, a bed bolster, driving means for reciprocating said slide, means adapted to support a die on the bed bolster, means adapted to support a co-acting die for cooperation with the die carried by the bed bolster, a movable frame, stock-feeding rolls carried by said frame, means drivingly connecting said frame to said slide-driving means for reciprocating said frame vertically in predetermined timed relation with said slide, means driven from said slide-driving means for operating said feeding rolls in predetermined phased relation with the movement of said feed roll-carrying frame, said die carried by the bed bolster being provided with a lift-out pin, a lift-out bar carried by said frame for operating said lift-out pin, the arrangement being such that when the frame is moved upwardly the stock-feeding rolls and the lift-out pin will raise the stock to a level clear of the bed die.

3. In a power press, a slide, a bed bolster, driving means for reciprocating said slide, means adapted to support a die on the bed bolster,

means adapted to support a co-acting die for cooperation with the die carried by the bed bolster, a movable frame, stock-feeding rolls carried by said frame, means drivingly connecting said frame to said slide-driving means for reciprocating said frame vertically in predetermined timed relation with said slide, means driven from said slide-driving means for operating said feeding rolls in predetermined phased relation with the movement of said feed roll-carrying frame, a scrap cutter carried by said frame, and means for actuating said scrap cutter from said slide-driving means in predetermined timed relation with the movement of said slide and said frame.

4. In a power press, a slide, means for reciprocating said slide, a prime mover for driving said slide-reciprocating means, a movable framework carried by the power press for reciprocal movement relative to said slide, means driven from said slide-driving means for reciprocating said framework vertically in predetermined timed relation with the movements of said slide, a pair of stock-feeding rolls carried by said framework, means driven from said slide-driving means for operating said stock-feeding rolls in predetermined timed relation with the movement of said framework, the construction being such that said feeding movement will occur while said framework is in a raised position whereby the stock may be fed in a raised position.

5. A power press as in claim 4 including in combination a bed bolster, a slide bolster carried by said slide, co-acting dies carried by the slide bolster and the bed bolster, a lift-out bar carried by said framework, stripper pins associated with said bed bolster dies actuated by said lift-out bar whereby the stock is moved to raised position by said stock-feeding rolls and said stripper pins.

6. A power press as in claim 4 including in combination a scrap cutter having at least one blade carried by said framework, means driven from said slide-driving means for actuating said scrap cutter in predetermined timed relation.

7. A power press as in claim 4 including in combination a scrap cutter carried by said framework and means for operating said scrap cutter as a function of the movement of said framework.

8. A power press as in claim 4 in which said stock-feeding rolls comprise two pairs of rolls positioned on each side of the slide.

9. A power press as in claim 4 in which said means driven from said slide-driving means for reciprocating said framework includes a pair of shafts, respective gears secured to said shafts each meshing with a gear of a gear train for reciprocating said slide, a pair of cams secured to respective shafts for rotation therewith, and draw bars actuated by said shafts secured to said framework.

10. A power press as in claim 4 in which said means driven from said slide-driving means for reciprocating said framework includes a pair of shafts, respective gears secured to said shafts each meshing with a gear of a gear train for reciprocating said slide, a pair of cams secured to respective shafts for rotation therewith, a pair of levers pivoted to the press, cam followers adapted to be actuated by said cams carried by said levers intermediate their ends and draw bars extending from the ends of said levers to said framework.

11. A power press as in claim 4 in which said means driven from the slide-driving means for

operating the stock-feeding rolls includes a shaft, a gear secured to said shaft for rotation therewith, said gear meshing with the gear of the gear train for reciprocating said slide, a rack, means actuated by the rotation of said shaft for reciprocating said rack, a pinion, and overrunning clutch means connecting said pinion to a roll feed drive shaft.

12. A power press as in claim 4 in which said means driven from the slide-driving means for operating the stock-feeding rolls includes a shaft, a gear secured to said shaft for rotation therewith, said gear meshing with the gear of the gear train for reciprocating said slide, a rack, means actuated by the rotation of said shaft for reciprocating said rack, a pinion, overrunning clutch means connecting said pinion to a roll feed drive shaft, said drive shaft including a section permitting relative movement longitudinally of the drive shaft while preventing relative rotational movement between said section and the shaft, the construction being such that the feed rolls may reciprocate relative to one portion of the feed roll drive shaft.

13. A power press as in claim 4 including in combination a scrap cutter one blade of which is carried by said framework, a second blade adapted to co-act with said first blade, means for mounting said second blade for reciprocal movement relative to the press frame, said means for reciprocating said framework including a shaft, means to rotate said shaft from the driving train for reciprocating said slide, an eccentric carried by said shaft, and a pitman connecting said eccentric to said second blade for reciprocating it in predetermined timed relation to the movement of the press slide.

14. A power press as in claim 4 including in combination a scrap cutter one blade of which is carried by said framework, a second blade

adapted to co-act with said first blade, means for mounting said second blade for reciprocal movement relative to the press frame, said means for reciprocating said framework including a shaft, means to rotate said shaft from the driving train for reciprocating said slide, an eccentric carried by said shaft, a pitman connecting said eccentric to said second blade for reciprocating it in predetermined timed relation to the movement of the press slide, and means for adjusting the position of said second blade whereby to vary the ambit of its travel.
